ELECTRICAL LIGHTING APPARATUS FOR DISPLAYING ADVERTISING MESSAGES ON A ROTARY DRUM

Jakob Asam, Merano, Italy, assignor to Informa S.R.L.,
Merano, Bolzano, Italy

Filed Dec. 20, 1972, Ser. No. 316,767

Claims priority, application Italy June 21, 1972

Term of patent 14 years

Int. Cl. D20—03

U.S. Cl. D96—12 R

Fig. 1

FIG. 1 is a perspective view, seen from a side and above, of an electrical lighting apparatus for displaying advertising messages on a rotary drum, showing my new design; FIG. 2 is a rear view of the apparatus.

I claim:

The ornamental design for an electrical lighting apparatus for displaying advertising messages on a rotary drum, as shown and described.
